UNITED STATES PATENT OFFICE.

LUDWELL D. LANSDALE, OF SUGAR LAND, TEXAS.

CONCENTRATING APPARATUS.

Application filed June 8, 1920. Serial No. 387,456.

To all whom it may concern:

Be it known that I, LUDWELL D. LANSDALE, a citizen of the United States, residing at Sugar Land, in the county of Fort Bend and State of Texas, have invented a new and useful Concentrating Apparatus, of which the following is a specification.

This invention is an apparatus for use in the manufacture of sulphuric acid and 10 the like.

One of the objects of the invention is to provide a simple apparatus, by means of which ordinary chamber acid may be treated and concentrated, to produce a high grade 15 chemically pure colorless acid. A further object is to provide an apparatus of the character mentioned, constructed of a material capable of withstanding the corrosive action of the acid, under all conditions. A 20 further object is to provide a simple and efficient means for maintaining the acid at a high temperature during the treatment, whereby the aqueous fumes may be driven off, and a highly concentrated product obtained. A further object is to provide a 25 concentrating apparatus constructed of units, which may be readily separated for purposes of repair, or for the substitution of new parts. A further object is to collect 30 the fumes driven off during the heat treatment, and to condense them, whereby they may be utilized as a byproduct.

The invention will be hereinafter fully set forth and particularly pointed out in the 35 claims.

In the accompanying drawing:

Figure 1 is a side elevation, partly in section, illustrating a concentrating apparatus constructed in accordance with the invention. Figure 2 is a top plan view, parts being broken away. Figure 3 is a detail sectional view illustrating one of the concentrating chambers. Figure 4 is a side elevation illustrating the apparatus for condensing 45 the aqueous fumes.

Referring to the drawing, 10 designates a tank constructed to receive and store ordinary chamber acid developed in the manufacture of sulphuric acid, the same having 50 an outlet pipe 11. The discharge end of the pipe 11, communicates with the inlet end of a concentrating conduit formed of a plurality of units or chambers 12. Each unit 12 is in the form of a pipe section, provided 55 with an upwardly projecting inlet end 13, and a downwardly projecting outlet end 14,

the outlet end of each unit being connected with the inlet end of an adjoining unit, the ends of the units being connected in suitable manner, as indicated at 15. Any number of 60 the units 12 may be connected in series as clearly illustrated in Figure 1. As shown, the series discharges into a condensing chamber C, where the concentrated acid is cooled in any desired manner, a coil D, being illustrated as performing this function.

The pipe units 12 may be constructed of any suitable acid resisting material. Each unit is wrapped with an electrical resistance wire 17, of the character commonly 70 employed in the manufacture of electrical heaters, and said wire is connected with a suitable source of electrical energy (not shown), so that the units 12 may be heated to a high temperature. Any desired heat 75 insulation may be provided to prevent radiation of the heat. It is preferred to use one of the well-known types of magnesia pipe covering indicated at 18, which is covered with an asbestos cement 19, and finally 80 wrapped in canvas or other fabric 20, which may be finished in any desired manner, for instance, by shellacing, to make it shrink sufficiently to produce a neat appearing job, and finally painting.

Leading from the tops of the units 12 are fume-escape pipes 22, which discharge into a fume collecting chamber 23, of any suitable material, surrounded by a water jacket 24, for the purpose of reducing the temperature of the gas fumes as they are discharged from the pipes 22. The fume collector may be constructed of any suitable material but is preferably lined with lead. Each unit 12 may also be provided with means indicated at 16 for connection of a thermometer, pyrometer, or the like. It will be noted that the conduit formed by units 10 is arranged in approximate U-shape in plan, so that portions thereof may be located on 100 both sides of the fumes collector, and the latter is located between the sets of pipes 22.

Leading from the fume collector 23 is a conduit 25, which discharges into a bottom chamber 26, of a condenser receptacle 27. 105 provided with a packing 28 of silica or other suitable material, the construction being similar to that of the well-known gas scrubber. Above the packing 28 is an outlet chamber 29, communicating with a discharge pipe 30, which leads to a second condenser receptacle 31 similar in all details to

the receptacle 27, and if desired the receptacle 31 may discharge into a third condenser receptacle 32, and so on, as many of said condenser receptacles being employed 5 as occasion may require. The discharge chamber 29 of the last condenser receptacle, is connected by a conduit 33 with a stack 34, an exhaust device such as a fan 35, being interposed between the conduit 33 and the 10 stack 34.

Discharging into the outlet chambers 29 of the condenser receptacles 27, 31 and 32, above the silica packing 28 are pipes 36, leading from a tank 37, containing liquid 15 acid, said tank being cooled in any suitable manner, such as by means of the coil 38, conventionally illustrated. The chambers 26 of the condensing receptacles are placed in communication with a receiving tank 39, 20 by means of drain pipes 40. The chamber for the fan 35 is also provided with a drain pipe 41, leading to the tank 39. The tank 39 is cooled in suitable manner, as by means of the coil 42 conventionally illustrated. 25 From the tank 39 the liquid acid is discharged into the inlet pipe 43, of a common type of air lift, the outlet branch 44 of which discharges into the tank 37 as shown.

30 In operation the tank 10 is supplied with chamber acid of any desired strength, from any suitable source. The chamber acid is discharged through the pipe 11 into the heating zones formed by the units 12, which 35 are connected to form a continuous conduit, of substantial length. As the chamber acid travels through the conduit, the light aqueous fumes are driven off by the heat generated by the coils 17, and are discharged into 40 the collecting chamber 23 by the pipes 22. As the acid travels progressively through the series of units 12, its degree of concentration gradually increases, and the concentrated acid is finally passed through the 45 cooling chamber C, from which it is discharged as a colorless chemically pure acid, of any desired strength up to 98.3 H₂SO₄.

It is to be understood that the strength of the acid delivered from the cooling chamber 50 C, may be varied either by increasing or reducing the quantity of chamber acid supplied to the apparatus, or by changing the distance that the acid is caused to travel.

The fan 35 in its operation, creates a suction, which induces a travel of the fumes 55 from the collector 23, through the various condensing receptacles 27, 31 and 32. As the fumes travel upwardly through the silica packing, they come into contact with a 60 body of liquid acid flowing in the opposite direction, from the tank 37, through the pipes 39. A certain portion of the fumes thus coming into contact with the liquid acid, are condensed and will flow through 65 the drain pipes 41, into the receiving tank

40, and as the condensed acid accumulates in said tank, it is delivered by the air lift to the tank 37, so that it is used over and over again in condensing fumes. Such fumes as pass the last condensing chamber 70 without condensation, will pass out of the stack 34.

The advantages of the invention will be readily appreciated by those skilled in the art to which it appertains. It will be particularly noted that a very simple and efficient apparatus has been provided, by means of which ordinary chamber acid may be chemically treated, and concentrated to produce a high grade chemically pure acid. 75 By employing the pipe sections 12, any number of units may be coupled together, as may be desired, and by constructing said pipes of a material capable of withstanding the corrosive action of the acid, a highly 80 efficient and durable apparatus is produced. By employing the electrical method of heating the pipe sections 12, the acid is maintained at a high and uniform temperature during its treatment, and the unit is symmetrically heated with respect to its axis. 85 Should one of the units 12 become damaged or unfit for use for any reason, it may be readily disconnected in a short time, and a new one quickly substituted. Thus shutting 90 down of the apparatus over long periods for purposes of repairs, is avoided. It will also be noted that a simple and efficient apparatus has been provided to recover and condense the fumes driven off during the 95 concentrating process.

Having thus explained the nature of the invention and described an operative manner of constructing and using the same, although without attempting to set forth all 105 of the forms in which it may be made, or all of the forms of its use, what is claimed is:—

1. In a concentrating apparatus of the character described a concentrating unit 110 consisting of a pipe-like section through which chamber acid may be caused to travel, means for symmetrically heating said unit, and means for carrying off the fumes.

2. In a concentrating apparatus of the character described a concentrating unit 115 through which chamber acid may be caused to travel, a heat medium supported by and surrounding said unit, and means for carrying off fumes.

3. In a concentrating apparatus of the character described a unit through which chamber acid may be caused to travel, a wrapping of electric resistance wires surrounding said unit, whereby the same may 125 be heated, and means for carrying off fumes.

4. In a concentrating apparatus of the character described a pipe section of acid resisting material through which chamber acid may be caused to travel, said pipe sec- 130

- tion having oppositely turned inlet and outlet portions, an intermediate fumes outlet, and a wrapping of electric resistance wire surrounding said unit, whereby it may be heated.
5. A concentrating apparatus of the character described comprising a conduit through which chamber acid may be caused to flow, said conduit being formed of a plurality of units connected in series, each unit having means whereby it may be independently heated, and means for carrying off the fumes from the heated acid.
10. A concentrating apparatus of the character described comprising a conduit through which chamber acid may be caused to flow, said conduit being formed of a plurality of units connected in series, and independent heating media surrounding the respective chambers, each unit having independent means for carrying off the fumes from the heated acid.
15. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, 45 fumes-escape pipes leading from the respective units to the collector, and means for cooling the concentrated acid.
20. A condensing apparatus of the character described comprising a conduit through which chamber acid may be caused to flow, said conduit being formed of a plurality of units connected in series and arranged in different horizontal planes in stepped relation, each unit having means whereby it may be independently heated, means for carrying off the fumes from the heated acid, and means for cooling the concentrated acid.
25. A concentrating apparatus of the character described comprising a conduit through which chamber acid may be caused to flow, said conduit being formed of a plurality of units connected in series, each unit having means whereby it may be independently heated, a fumes-collector, 30 fumes-escape pipes leading from said units to said collector, and means for cooling the concentrated acid.
30. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, 35 fumes-escape pipes leading from the respective units to the collector, and means for cooling the concentrated acid.
35. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, 40 fumes-escape pipes leading from the respective units to the collector, and means for cooling the concentrated acid.
40. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, 45 fumes-escape pipes leading from the respective units to the collector, and means for cooling the concentrated acid.
45. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, 50 fumes-escape pipes leading from the respective units to the collector, and means for cooling the concentrated acid.
50. A concentrating apparatus of the character described comprising a conduit through which chamber acid may be caused to flow, said conduit being formed of a plurality of pipe-like units arranged in series in different horizontal planes and in stepped relation, means whereby said units may be independently heated, a fumes-collector, fumes-escape pipes leading from the respective units to the collector, and means for cooling the concentrated acid.

In testimony whereof I have hereunto set my hand.

LUDWELL D. LANSDALE.
